EDGE ROLL FOR SPRING CUSHION ASSEMBLIES

William F. Richardson, Carthage, Mo., assignor to Flex-O-Lators, Inc., Carthage, Mo., a corporation of Missouri

Application February 20, 1952, Serial No. 272,532

5 Claims. (Cl. 5—360)

1

This invention relates to new and useful improvements in spring cushion assemblies, and relates particularly to a padded edge roll for use in connection with said spring cushion assemblies. In many types of spring cushion assemblies, a padded edge roll is often applied to the bare spring assembly around the marginal edges thereof. The usual upholstery and covering is then applied over the springs and edge roll. The edge roll protects the overlying upholstery against wearing contact with the wires of the spring assembly at the edges of the cushion, this area normally being subject to the greatest wear. The edge roll also provides greater comfort for the user of the cushion, and better protection for the springs. The provision of an improved edge roll of this class is the principal object of this invention.

Another important object is the provision of an edge roll of the class described which has the initial form of a flattened, elongated strip adapted to be folded along its longitudinal mid-line and fitted about the marginal edge of a spring assembly with the edge portions thereof disposed respectively on opposite sides of the end loops of the component springs, and having novel means for securing said edge portions together through said spring loops, whereby to fasten said edge roll firmly in position on said spring assembly.

A further object is the provision of an edge roll as described wherein the means for securing the edge portions of the roll together comprises a plurality of resilient heads or detents carried by one edge portion of the roll and adapted to be snapped through holes formed in the opposite edge portion of the roll, whereupon they expand to prevent withdrawal.

A still further object is the provision of an edge roll of the class described wherein the resilient heads or detents are formed in a continuous strand of wire extending longitudinally of the edge roll, said wire also serving the functions of strengthening and stiffening the edge roll, and of holding the component parts thereof in assembly.

Other objects are extreme economy and simplicity of construction, ease and convenience of application requiring no tools or special equipment, and adaptability for use in many types of spring cushions.

With these objects in view, as well as other objects which will appear in the course of the specification, reference will be had to the drawing, wherein:

2

Fig. 1 is a fragmentary plan view of a spring cushion assembly showing an edge roll embodying the present invention applied thereto, with parts broken away.

5 Fig. 2 is an enlarged fragmentary section taken on line II—II of Fig. 1.

Fig. 3 is an inner face view of a section of the edge roll separated from the spring assembly and laid flat, with parts broken away.

10 Fig. 4 is a section taken on line IV—IV of Fig. 3.

Fig. 5 is a section taken on line V—V of Fig. 3.

Like reference numerals apply to similar parts throughout the several views, and the numeral 15 2 applies to a spring assembly such as is commonly used in spring cushions, and comprising a plurality of spool-shaped helical springs 4 arranged in parallel, spaced apart rows with their axes substantially parallel. Each of said springs 20 has a substantially circular top loop 6 and bottom loop 8, said top and bottom loops lying respectively in planes forming the upper and lower faces of the assembly. The top loops 6 of adjacent springs in each row of springs overlap 25 slightly, and are joined by a plurality of helical binder coils 10 which extend across the upper face of the assembly transversely to the rows of springs, and each which extends between corresponding pairs of springs in each row, coiling 30 about the overlapping portions of loops 6. Binder coils 12 similarly join the bottom loops 8 of the springs, as indicated in Fig. 2. The binder coils may be secured by wrapping the end portions thereof about a convenient loop of springs 35 4, as indicated at 14. A binder coil 16 similar to coils 10 and 12 may be disposed about the marginal edge of each face of the spring assembly, coiling about the outer edge portions of the end loops 6 and 8 of springs 4, as shown, and a 40 straight wire 18 may be threaded if desired through each of said marginal coils, in order to hold the assembly more firmly in shape. It is to be understood however, that the specific arrangement of springs 4 shown, and the means 45 for joining them together to form a cushion assembly, are not intended in any way to be restrictive, nor to preclude other arrangements or joining means, since the edge roll forming the subject matter of this invention may be applied to many different types of spring assemblies.

The edge roll 20 comprises a tubular sheath 22 which may be formed of any suitable pliable sheet material, but is preferably made of a tough, heavy paper. A heavy grade of paper known as 55 "X-crepe" paper has been found particularly

satisfactory, since while possessing adequate strength, it is quite pliable and also provides a "two-way" stretch which imparts an added degree of flexibility to the completed edge roll. As shown, the sheath is formed of a single strip of paper folded longitudinally to form a flat tubular sheath, with the edge portions 24 of the strip overlapping at one edge of the sheath, as best shown, in Figs. 3 and 4, and on the face of the sheath which will be the inner face after the sheath is folded longitudinally. Disposed within sheath 22 is a suitable padding material, which as shown comprises a plurality of superimposed strips 26 of a thick, soft pulp paper, and which further may be regularly indented to form what is ordinarily known as "waffle" paper. This indentation provides a greater degree of yieldability. It is apparent, however, that various other types of padding material could be made.

Referring principally to Figs. 3, 4, and 5, it will be seen that a plurality of holes 28 are formed through the sheath and padding material adjacent one edge of the sheath, said holes being regularly spaced apart longitudinally of the sheath. It will be noted also that said holes pierce the overlapping edge portions 24 of the strip forming sheath 22. A similar series of holes 30 are formed through the sheath and padding adjacent the opposite edge of the sheath. Holes 28 and 30 are aligned transversely of the sheath, so as to be brought into registering relation when the sheath is folded longitudinally along its midline, as shown in Fig. 2. A resilient wire 32 extends longitudinally of the edge roll, lying against the outer face of sheath 22 and intersecting holes 28. At each hole 28 a loop or bight is formed in the wire to present a resilient head or detent 34 which projects inwardly through hole 28 and extends outwardly from the inner face of the sheath. As detailed in Fig. 5, each head 34 includes a pair of parallel reaches 36 extending at right angles, to the body of wire 32, having a length equal to substantially twice the thickness of the padded sheath, and being normally spaced apart a distance equal to the diameter of hole 28, so as to fit snugly therein. At the inner ends of reaches 36, the wire is rebent oppositely outwardly longitudinally of the sheath to form shoulders 38 confronting the inner face of the sheath. From the outer end of said shoulders, the wire is rebent longitudinally of the head, and extends in converging reaches 40 to a rounded point 42.

In applying the edge roll, sheath 22 is folded longitudinally along its midline as shown, and disposed about the border of the top face of spring assembly 2, with the edge portions thereof disposed respectively above and below the top loops 6 of springs 4. Each of heads 34 is then pushed through hole 30 in the opposite edge portion of the sheath. Point 42 of the head facilitates the insertion thereof into hole 30. As it is pushed through hole 30, the head 34 is deformed resiliently, shoulders 38 being moved into overlapping relation, to permit its passage through the hole. When shoulders 38 have passed entirely through hole 30, they expand resiliently to engage the outer surface of the sheath, thereby preventing withdrawal of the head. Heads 34 are of course disposed to extend into the interior of the spring assembly as shown in Fig. 2, so as not to interfere with the upholstery which is later applied over the outer surface of the assembly. Also an edge roll may if desired be applied to the bottom loops 8 of springs 4, as shown in

Fig. 2. The edge roll is thus secured firmly to the spring assembly, since heads 34 connect the edges of the sheath through spring loops 6 and 8, and on the inner side of marginal coil 16 and straight marginal wire 18. While the drawing shows the edge roll folded about the marginal binder coil 16, it is apparent that it could be folded about a common straight marginal wire as more commonly used in cushion spring assemblies, or that if desired it could be used as a substitute for and in lieu of any marginal wire.

Thus it is apparent that an edge roll possessing several advantages has been produced. It is extremely simple and economical in construction. It may be applied by hand without tools or other special equipment. It may be applied to virtually any type of cushion spring assembly without change or special adaptation of any kind. The heads 34, since they pierce the entire sheath and pass through the overlapping portions of the paper strip forming the sheath, serve additionally to hold all parts of the edge roll in assembly, both before and after application to the spring assembly. The formation of heads 34 in a wire extending longitudinally of the edge roll has at least two important advantages. Firstly, a continuous wire attached at spaced points to the sheath provides tensile strength and any desired degree of stiffness in the edge roll. This is particularly valuable in instances wherein the edge roll, as described above, serves in lieu of any other marginal binder or wire. Secondly, the wire connection between successive heads holds the heads in their expanded or operative position, preventing accidental withdrawal thereof from holes 30. It will be noted that as each head is compressed to enter the corresponding hole 30 during the application of the edge roll, said compression will necessarily cause a slight localized buckling or deformation of the sheath between that head and the next adjacent head, since compressing the head effectively shortens the length of the wire. However, such local deformation will not occur during the application of a general load to the cushion such as encountered in general use, and furthermore, any such ordinary deformation of the cushion places the wire in tension, which further tends to hold the heads 34 in their expanded operative form.

While I have shown a specific embodiment of my invention, it is apparent that many minor changes of material, construction, and operation could be made without departing from the spirit of the invention as defined by the scope of the appended claims.

What I claim as new and desire to protect by Letters Patent is:

1. An edge roll for spring mattress assemblies comprising an elongated flattened pliable padded member adapted to be folded longitudinally along its midline, said padded member having a series of longitudinally spaced apart holes formed therethrough adjacent one longitudinal edge thereof, and a resilient wire extending longitudinally of said padded member adjacent the opposite longitudinal edge thereof, said wire being secured to said padded member at longitudinally spaced apart points and being formed to present a series of longitudinally spaced transversely compressible heads each in transverse alignment with one of said holes and adapted to be snapped through said hole when said padded member is folded.

2. An edge roll for spring mattress assemblies comprising an elongated flattened pliable padded

member adapted to be folded longitudinally along its midline, said padded member having like series of longitudinally spaced apart holes formed therethrough respectively adjacent the opposite edges thereof, and a resilient wire extending longitudinally of said padded member and having bights formed at intervals therein to present transversely extending heads extending through the holes of one of said series of holes, said heads being normally too large to pass through the holes of the other series but being resiliently compressible to pass therethrough.

3. The structure as in claim 2 wherein the bights formed in said wire lie in a plane coinciding with the body of said wire, and wherein each bight forms a substantially triangular head with its apex extending outwardly from the wire body, the wire reaches forming said apex being rebent inwardly to form shoulders substantially parallel to the wire body, and rebent again at right angles to form parallel reaches joining said head to said wire body.

4. The structure as in claim 2 wherein the bights formed in said wire lie in a plane coinciding with the body of said wire, and wherein each bight forms a substantially triangular head with its apex extending outwardly from the wire body, the wire reaches forming said apex being rebent inwardly to form shoulders substantially parallel to the wire body, and rebent again at right angles to form parallel reaches joining said head to said wire body, said last named

parallel reaches being normally spaced apart a distance substantially equal to the diameters of the holes in said sheath.

5. An edge roll for spring mattress assemblies comprising a strip of pliable sheet material folded longitudinally to form a flat tubular sheath with the edge portions of said strip overlapping at one edge of said sheath, padding material disposed in said sheath, said padded sheath having a series of longitudinally spaced holes formed therethrough adjacent one edge thereof and piercing the overlapping portions of said strip, and a like series of holes formed therethrough adjacent the opposite edge thereof, and a resilient wire extending longitudinally of said sheath in intersecting relation with said first series of holes, said wire having bights formed therein at intervals to present loops each extending through one of the holes of said first series, the extended portion of each loop being formed to present an enlarged head normally too large to pass through said hole, but being resiliently compressible to pass through the corresponding hole of said second series when said sheath is folded longitudinally along its midline.
